UNITED STATES PATENT OFFICE

121,343

DESIGN FOR A PANEL FOR AN ASTROLOGICAL AND MYSTIC ROBOT

Joseph P. Wilson, Columbia, S. C.

Application December 14, 1939, Serial No. 88,894

Term of patent 7 years

To all whom it may concern:

Be it known that I, Joseph P. Wilson, a citizen of the United States, residing at Columbia, in the county of Richland and State of South Carolina, have invented a new, original, and ornamental Design for a Panel for An Astrological and Mystic Robot, of which the following is a specification, reference being had to the accompanying drawing, forming part thereof.

Fig. 1 is a front elevational view of a panel for an astrological and mystic robot, showing my new design;

Fig. 2 is a top plan view thereof;

Fig. 3 is an end elevational view; and

Fig. 4 is a sectional view taken on the line 4—4 of Fig. 1.

The characteristic features of the design consist of a section of glass having an uneven surface, with zodiac and design emulative of the human eye being in general association.

I claim:

The ornamental design for a panel for an astrological and mystic robot, substantially as shown and described.

JOSEPH P. WILSON.
